UNITED STATES PATENT OFFICE.

CHARLES B. GILMORE, OF CHICAGO, ILLINOIS, ASSIGNOR TO WILLIAM H. PLUNKETT, OF CHICAGO, ILLINOIS.

DUST-MOP.

1,230,476.

Specification of Letters Patent. Patented June 19, 1917.

Application filed August 24, 1916. Serial No. 116,581.

To all whom it may concern:

Be it known that I, CHARLES B. GILMORE, a citizen of the United States, residing at Chicago, in the county of Cook and State 5 of Illinois, have invented certain new and useful Improvements in Dust-Mops, of which the following is a specification.

This invention relates to mops of the general character commonly known as oil mops, 10 or dust mops, designed for cleaning floors and various places about the house.

One of the salient features of this invention resides in the fact that the mop cloth is detachably connected to the body portion 15 of the mop so that it can be readily detached and boiled or otherwise cleaned and easily connected again to the body portion.

Another object is to provide a mop of such construction that the handle may be 20 swung on its pivot so as to be disposed either above the mop for cleaning floors and the like, or below the mop for cleaning picture moldings, the tops of high pieces of furniture, and other inaccessible places.

Still another object is to so connect the 25 mop handle to the body of the mop that it will be frictionally held in any position to which it may be moved but can be easily adjusted to any other desired position.

One practical and preferred embodiment 30 of my invention is illustrated on the accompanying sheet of drawings, from an inspection of which when considered in connection with the following description my invention should be readily understood. Referring to the drawings,—

Figure 1 is a top plan view of a mop embodying my invention, certain parts being shown in section;

Fig. 2 is a side elevation partially in section of the mop shown in Fig. 1; and

Fig. 3 is a sectional view on the line 3—3 of Fig. 2.

From an inspection of the drawings it 45 will be observed that the body portion of the mop is of substantially U-shaped construction, comprising the sides 5 and 6 terminating at the open end of the U in diverging oppositely disposed arms 7 and 8 50 respectively. This body portion is formed integrally of a strip or bar of stiff metal, and the arms projecting laterally from the main portion of the body are adapted to be inserted back of legs of furniture and 55 into corners and other inaccessible places

which cannot ordinarily be reached with round, triangular or other customarily shaped mops.

The cloth which is carried by the body portion comprises a fabric portion 9 provided with the mass of thickly bunched mop strands 11. These strands are securely fastened to the portion 9 which is preferably formed of canvas or other suitably heavy fabric, the ends of which are sewed 60 so as to provide pockets 12 adapted to receive the ends 7 and 8 respectively of the laterally projecting arms. The center of the cloth is provided on its inner face with a socket member 13 adapted to receive a 65 ball member 14 rigidly fastened to the crown or closed end of the U-shaped body. This ball and socket connection is similar in construction to the ordinary snap glove fastener and provides a detachable fastening by 70 means of which the cloth is secured to the body portion remote from the laterally projecting arms. When it is desired to remove the cloth for the purpose of cleaning it by boiling or otherwise the socket 13 is un- 75 snapped from the ball 14, whereupon the ends of the cloth may be withdrawn from the arms 7 and 8, thereby completely freeing the cloth from the body. To replace the cloth the arms are inserted into the pockets 80 12 formed in the ends of the cloth and the socket member 13 is then reengaged with the ball member 14. It will thus be obvious 85 that the cloth may be readily and easily detached from and reattached to the body portion of the mop. 90

The handle comprises the ordinary wooden pole (not shown) which fits into the socket 15 of a shank 16 having bifurcated ends 17 and 18, respectively, adapted to be 95 disposed between the parallel sides of the body portion to which they are pivotally connected by a pintle or rivet bolt 19. For the purpose of providing a frictional engagement between the bifurcated ends of the shank and the sides of the body portion a coiled expansion spring 21 is mounted upon the pintle 19 so that its expansive action forces the bifurcated ends of the handle-shank into frictional engagement with the 100 side members of the mop body, thereby frictionally holding the handle in any position in which it is placed. The handle may be adjusted, however, to any other position by swinging it about the body portion against 105 110

the frictional force exerted by the spring 21. From Fig. 2 it will be obvious that the handle may be swung down substantially into the plane of the body of the mop, as shown in full lines, to permit the mop to be inserted beneath low pieces of furniture without marring the same. The handle may also be swung in a counterclockwise direction, viewing Fig. 2 entirely through between the parallel side members of the mop body into the dotted line position shown in Fig. 2, so that the cloth is disposed above instead of beneath the handle to enable the mop to be used on picture moldings or upon the tops of pictures or high pieces of furniture or other inaccessible places.

The construction and many of the advantages of my invention should be appreciated from the foregoing without further description and it should be understood that the size, shape, proportion and arrangement of the various parts may be varied within

considerable limits without departing from the essence of the invention as defined in the following claims:

I claim:

1. A dust mop, comprising a body portion provided at one end with diverging oppositely extending arms, a cloth, and means for detachably connecting said cloth to said body portion comprising pockets in the ends of the cloth adapted to receive the ends of said arms, and a device for detachably securing the cloth to said body portion at the end remote from said arms.

2. A dust mop, comprising a body portion provided with divergent oppositely projecting rigid arms, a mop cloth provided at its ends with pockets adapted to receive the ends of said arms, means for detachably securing the mop cloth to said body portion intermediate the ends thereof, and a handle connected to said body portion.

CHARLES B. GILMORE.
